UNITED STATES PATENT OFFICE.

JOHN JAMES McMILLAN, OF NEW YORK, N. Y.

SCHOOL-DESK.

1,296,415.

Specification of Letters Patent.

Patented Mar. 4, 1919.

Application filed October 24, 1918. Serial No. 239,540.

To all whom it may concern:

Be it known that I, JOHN JAMES McMILLAN, a citizen of the United States, and a resident of the city of New York, borough of Manhattan, in the county and State of New York, have invented a new and Improved School-Desk, of which the following is a full, clear, and exact description.

This invention relates to school furniture, and has particular reference to combined desks and seats, for schoolroom or similar purposes. Among the objects of the invention is to provide a suitable support for a desk that will afford the maximum amount of comfort to the pupil with respect to the disposition of his feet and legs.

Another object of the invention is to provide a combination desk and seat with facilities for adjusting the height of either the desk or the seat independently of the other whereby to accommodate the structure to the stature of the pupils.

A still further object of the invention is to improve the structural details of the desk body and means for manipulation thereof.

The foregoing and other objects of the invention will be fully set forth hereinafter and specifically claimed, and while the accompanying drawings disclose the best form 30 of the invention now known to me, it is to be understood that the various details of construction may be altered somewhat in design, material, or other minor respects without departing from the spirit of the invention.

Figure 1 is a rear elevation of my invention, portions being broken away to better show the construction.

Fig. 2 is a vertical section on the line 40 2-2 of Fig. 1, the parts being in normal position.

Fig. 3 is a view similar to Fig. 2 but showing the movable parts of the desk elevated and the seat folded to upright position.

Fig. 4 is a transverse section on line 4-4 of Fig. 2 and indicating the seat and desk in bottom plan.

Fig. 5 is a detail of the seat joint, the parts 50 being in section on the line 5-5 of Fig. 4.

Fig. 6 is a fragmentary side elevation of the desk showing especially the means for supporting the leaf, the view being as though seen from the line 6-6 of Fig. 4.

Fig. 7 is a sectional detail on the line 7-7 of Fig. 6.

Referring now more specifically to the drawings, I show a combined desk and seat structure comprising a pedestal 10 having a base 11 adapted to be fastened firmly to the floor. The pedestal above the base is substantially straight and relatively slender but of ample strength for practical purposes. This element occupies, therefore, a minimum amount of space beneath the desk and whereby the utmost freedom for the child's feet and legs is provided. The pedestal in cross section will be observed to be of segmental form, rounded or cylindrical in front at 12, and having a vertical channel or guideway 13 at the rear, with parallel side edges bounded by a pair of ribs 14. Between the channel 13 and the front rounded surface 12 is a vertical, flat elliptical bore 15, and communicating with said bore at both the front and the rear thereof are slots 16 and 17 lying in the same vertical plane intersecting the vertical center of the bore 15. At the upper end of the pedestal, spanning the rear portion thereof, is a bridge 18 constituting the upper end of the slot 17 and in which is fitted a set screw 19.

The desk body as a whole is shown at 20, the same comprising rigidly connected front, top, side, and rear portions 21, 22, 23 and 24 respectively. The front panel 21 is preferably made of wood and curved to conform to the back of the child sitting in front thereof. The side portions are preferably of sheet metal and provided at the bottom and rear edges with inwardly projecting flanges 23^a and 23^b respectively. The flanges 23^a, in addition to serving to strengthen the side members, constitute supports for the upwardly removable bottom panel 25. The rear flanges 23^b extending around the ends of the rear panel 24 serve to strengthen the joints between these parts. The connection between the side pieces 23 and the front panel 21 may be effected through ears 23^c formed integral with the side members and through which screws 26 may project into the front panel. In addition to these fixed parts, the body includes a leaf 27 shown supported in a peculiar way upon and between the side pieces 23. This leaf is made, preferably, and chiefly of wood but includes at its ends a pair of metallic plates 28 each of which comprises a wide hinge portion 28^a and a narrow strap portion 28^b. Beneath the front edge portion of the leaf 27 is a cleat 29 arranged substantially at right an-

gles to the under surface of the leaf, serving several important functions, as follows: First, it stiffens the leaf and offsets any liability of the leaf to warp or sag endwise between the hinges; secondly, it constitutes in connection with the wide or lobe portions 28^a of the hinge plates immediate hinge connections or supports; and, thirdly, as will be noted especially in Fig. 3, the cleat 29, in connection with the rear or under surface of the leaf 27, constitutes a book rest, so that the child may read or study with the book in proper upright position without requiring him to hold the book.

15 The side plates 23 have upper rear extensions 30 in each of which is formed a pivot hole 31 and an arc-shaped slot 32 concentric with said hole 31. The slot extends from a point in front of the pivot hole 31 on substantially the same level thereof down slightly beyond the vertical. (See Fig. 6.) The main pivot members consist of screws or bolts 33 extending freely through the pivot holes 31 and through holes 34 formed in the lobe portions 28^a of the plates aforesaid and directly into the ends of the cleat 29. A nut 35 fitted into a square socket 36 formed in the end of the cleat 29 serves to make a reliable connection for the bolt and prevents rotation of the bolt with respect to the cleat and leaf, so that when the bolt 33 is screwed into the end of the cleat through the nut and the two aligned holes 31 and 34, the bolt becomes fixed with respect to the leaf and its cleat and so may turn freely in the hole 31 during the movement of the leaf. Adjacent to each pivot bolt 33 is a stop member in the form of a short screw bolt 37 fitted in the lobe portion 28^a and extending freely through the slot 32. This description of each hinge connection will be understood as being applicable to both ends of the leaf. The stop member 37 is adapted to strike against the wall of the slot 32 at each end thereof. As shown in Fig. 6, the stop member limits the downward swing of the leaf, and obviously when the leaf is swung upward the same stop member strikes against the lower end of the slot and prevents the leaf from pounding too strongly against the top panel 22 of the desk body. The hinge connections, including the metallic members in close connection with each other and the pivot bolts and stop bolts, are exceedingly strong and durable. The bottom panel 25 is adapted to rest loosely upon the flanges 23^a, and so for the purpose of cleaning the desk from time to time the panel may be removed by simply 60 swinging it upward, as shown in Fig. 3, leaving it free to be withdrawn from the desk body, if desired, a matter of considerable importance in view of the fact that school desks are so apt to collect scraps of paper, fragments of luncheon, or other germ

carriers. When the janitor is sweeping, it is a simple matter for him to knock the panel 25 upward for the purpose of dumping the refuse on the floor where it will be swept up along with the other litter.

70

The means for supporting the desk body upon the pedestal consists of a combined yoke and shank, made preferably as a single forging or the like, the yoke being shown at 38 and the shank at 39. The yoke comprises two arms having U-shaped connection with the upper end of the shank and having rigid connection with the inner or rear face of the front panel 21, the connection being effected finally by means of countersunk screws 40. The upper ends of the yoke arms are bent backwardly at 38^a and so support the top panel 22. The shank 39 conforms in cross section to the bore 15 in which it is vertically adjustably fitted. The set screw 19 is adapted to bear directly against the rear face of the shank 39 whereby it constitutes a temporary holder for the desk body while the seat is being adjusted.

80

85 The seat 41 may be of any suitable construction, including a metallic rim 42, portions of which terminate in parallel ears 43 constituting portions of the hinge structure. 44 is a bracket having at least one arm but preferably two, as shown, leading forward 95 and upward from the pedestal terminating in a tongue 45 lying in a vertical plane between the ears 43 and 43'. Each of the tongues is provided with a central hole 46 for a pivot member 47, and concentric with said hole is an arc-shaped slot 48, similar to the slot 32, through which a stop member 49 projects loosely and is fixed in the pair of parallel ears 43 and 43'. The stop member 49 is adapted to strike against the upper and lower ends of the slot 48 and so limit the upward and downward movements respectively of the seat. The bracket, as shown in Fig. 4, has a rear concavity conforming to the curved surface of the pedestal, and a shank 110 or bolt 50 projects rearwardly therefrom through the slot 16, shank 39 and slot 17 into the guide space between the ribs 14 where a washer 51 and nut 52 serve to clamp the bracket and seat at any desired elevation 115 along the slot 16. The washer 51 has flat edges coöoperating with the ribs 14 along which the washer is guided in the adjustments aforesaid, while the nut 52 may readily be manipulated with a special T wrench 120 from the rear. The shank 39 may, if desired, be provided with a vertical slot in order to effect the various adjustments of the desk body prior to making the same secure through the set screw 19 and locking bolt 125 of shanks 50, but for all practical purposes I prefer to employ simply a series of holes 39' through the shank, and through any one of which the bolt 50 may pass. Initially, in assembling the parts after the pedestal is 130

fixed in position, the desk shank 39 will be slipped into the bore 15 and will be locked momentarily at the desired elevation, according to the pupil who will use the desk, by means of the set screw 19, leaving at least one of the holes 39' open to the slot 16. The seat in front of the pedestal will then be adjusted as to height by passing the bolt 50 rearward through the hole 39', which will afford the elevation desired for the pupil using such seat. The nut 52 will then be adjusted and tightened, completing the adjustment and firmly fixing the elevation or position of the desk body. The form of bracket 44 with respect to its two arms and the manner of fitting it to the front cylindrical surface of the pedestal insures maximum rigidity and strength, and yet the entire construction is so designed as to afford maximum floor space for the janitor when the parts are adjusted, as shown in Fig. 3, giving ample opportunity for thorough cleaning of the floor. Furthermore, there are no projecting angles or corners that are apt to injure the children or cause unnecessary wear and tear on their clothing or school supplies. Obviously, the desks and seats are made of different sizes; and in connection with the adjustability of the desk and seat portions independently of each other, it is an easy matter for proper adjustment to be made to suit every individual child, a matter of vast importance in view of the present and proper demand for correct seating and desk facilities, for hygienic reasons.

I claim:

1. In a school desk, the combination of a pedestal having a longitudinal bore and front and rear slots lying in the same plane on opposite sides of the bore and communicating therewith, a clamping member projecting through said slots and intercepting the bore, and a vertically adjustable member having a shank fitted in said bore and held in place by said clamping member.
2. In a school desk, the combination of a pedestal having a longitudinal bore, a desk body adjustably supported above the pedestal and having secured thereto a combined yoke and shank member, the yoke serving to reinforce and stiffen the body and the shank being fitted in said bore, and means to

clamp the shank at any desired position in said bore of the pedestal.

3. In a school desk, the combination of a 55 pedestal, a desk body above the pedestal, a combined yoke and shank, the yoke portion being U shape and fixed to the inner surface of the body, serving to reinforce and stiffen the same, while the shank portion extends downward along the pedestal, and clamping means acting between the pedestal and the shank and locking the desk body at any desired elevation with respect to the pedestal. 60

4. In a school desk, the combination of a pedestal having vertically aligned slots and a bore between the slots, the upper end of one of the slots being bounded by a bridge, a desk body above the pedestal, supporting 70 means for the body, including a rigid shank projecting into the bore, means acting through said bridge against the shank to temporarily hold it and the body in the desired elevation, and clamping means acting 75 through said slots and shank to permanently fix the elevation of the desk body. 65

5. In a school desk, the combination with the relatively fixed parts of the desk body, of movable leaf and pivot connections between the leaf and the other parts of the body serving to constitute the leaf into a writing desk top in one position and as a book support for reading or studying in its opposite position, the under surface of the 85 leaf being provided with a cleat as a book support, and the hinge connections including stop members to limit the swinging movement of the leaf in both directions. 80

6. In a school desk, the combination of a 90 pedestal having front and rear slots and a bore between and communicating with the slots, a clamping member passing through said slots and bore, a seat bracket carrying the clamping member, and a desk body including a shank adjustable vertically in said bore and having a series of holes through any one of which said clamping member is adapted to pass whereby the seat bracket and desk may be severally adjusted vertically and fixed in position by means of the single clamping member. 95 100

JOHN JAMES McMILLAN.
